(57) **CLAIM**

The ornamental design for a pull rope, as shown and described.

DESCRIPTION

FIG. 1 is a front perspective view of a pull rope showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The claimed design is shown with a symbolic break in its length. The appearance of any portion of the article between the break lines form no part of the claimed design.
